UNITED STATES PATENT OFFICE.

CARL THOMAS ANDERSON, OF MADISON, WISCONSIN.

DESIGN FOR A DESK.

61,355.

Specification for Design.

Patented Aug. 15, 1922.

Application filed December 12, 1921. Serial No. 521,943. Term of patent 14 years.

To all whom it may concern:

Be it known that I, CARL THOMAS ANDERSON, a citizen of the United States, residing at Madison, in the county of Dane and State of Wisconsin, have invented a new, original, and ornamental Design for a Desk, of which the following is a specification, reference being had to the accompanying drawing, forming part thereof.

The figure is a general view of my desk completely assembled.

I claim:

The ornamental design for a desk substantially as shown.

CARL THOMAS ANDERSON.
